REVERSING SWITCH

Howard C. Snyder, Ashland, Ky., and Stuart W. Pollock, Detroit, Mich., assignors to Dexco, Inc., Detroit, Mich., a corporation of Michigan

Application January 20, 1955, Serial No. 482,933

8 Claims. (Cl. 200—153)

This invention relates to electrical switches and to manually actuated motor-reversing switches in particular.

The principal object of our invention is to provide a motor-reversing switch that is more compact in design, smaller in size and more economical in manufacture than those now in use.

Another object is to provide a switch of the aforesaid type which, although compact, is rugged in construction such that servicing is required at infrequent intervals.

Still another object is to provide a switch that is fully enclosed against entry of dust and foreign materials, yet easily and quickly disassembled when servicing is required.

Other objects and advantages will be apparent from the following description which, taken in conjunction with the accompanying drawings, illustrates and describes a preferred embodiment of our invention.

In the drawings,

Fig. 1 is a plan view of our improved switch with the housing cover removed;

Fig. 2 is a sectional view taken on the line 2—2 of Fig. 4;

Fig. 3 is a top perspective view of the switch with the top cover removed;

Fig. 4 is a sectional view, on an enlarged scale, taken along the line 4—4 of Fig. 3;

Fig. 5 is a sectional view along line 5—5 of Fig. 4; and

Fig. 6 is a sectional view along the line 6—6 of Fig. 4.

Referring to the drawings, it will be seen that the switch is mounted in a heavy base 10 of metal, preferably aluminum or steel. The base 10 extends upwardly at its marginal portion and forms a housing for the switch parts as well as a mounting therefor, a rectangular cavity being provided. Integrally formed lugs 12 are provided at each corner of the base for securing the switch to a bench, wall or control panel. The base 10 is also provided with four integrally cast internal lugs 14 which terminate in the upward direction at approximately the line which separates the base and cover 16. The last is preferably a relatively heavy-section casting of steel or aluminum and is designed to fit around a marginal lip 18 formed on the top of the sides and ends of the base, as illustrated.

The operating mechanism of the switch is mounted on a saddle-member 20 of cast metal, which saddle is, in turn, secured at each side to side-pieces 22, 24, by cap-screws 26. The side-pieces are of relatively thick section metal and have integral contoured outer sections 28, 30, which, when the switch is assembled, rest on the central upper edges of the sides of the base, as indicated by reference numeral 32' (Fig. 4). The cover 16 is formed with side openings which are adapted to receive the contoured sections 28, 30, such that when the switch is assembled, a smooth, tight-fitting, casing is provided.

The side-pieces 22, 24, have ears 25 which are secured to the internal lugs 14 by cap screws 32; thus it may be seen that the saddle 20 is firmly secured in place in the base 10 by attachment of the side-pieces 22, 24, to which the saddle is secured.

Mounted on the saddle 20 by means of screws 34 are four insulating blocks 36 of suitable high-dielectric-strength material. Each of said blocks carries a pair of spaced contacts 38 securely fastened thereto. Each contact has an integral outwardly extending leg 40 on which is mounted a binding post provided with a knurled and bifurcated nut 42.

The blocks 36 each carry adjacent their inner ends, an upstanding lug 44 on which is pivotally mounted a contact arm 46. The lugs 44 may be mounted on the blocks in any suitable manner, such as by set-screws or the like. The arms 46 are mounted on the lugs 44 by headed pins 47 or other suitable means. Coil springs 48 mounted in recesses formed in the lugs 44 and arms 46, as illustrated, urge the arms into contact-closing position, as will be more fully explained below.

Each of the arms 46 carries a contact bridging bar 50 at its outer end. The bars 50 are provided with spaced contact points 52 which are adapted to engage similar contact points 54 mounted on the stationary contacts 38. The bars 50 are loosely retained in the ends of arms 46 under pressure of coil springs 56 (Fig. 2) which permit the arms 50 to align automatically when the mating contact points 52 and 54 are engaged.

The arms 46 each carry a roller 58 at their inner ends, the rollers being disposed such that they engage cams 60, 62. The latter are formed of dielectric material and are rigidly mounted on a shaft 64. The shaft 64 (see Fig. 4) has an enlarged central portion 66 to which the cams 60 and 62 are secured by means of cap screws 68 and reduced end portions 70, 72, which are journaled in the side pieces 22, 24, by the ball bearings 74, 76. The end portion 72 is elongated and mounted on the operating handle structure of the switch.

The operating handle structure comprises a casting 78 provided with a handle 80 which, in turn, carries a manually engageable knob 82.

To lend rigidity to the saddle assembly and to prevent flash-over between contact points, a shield 84 is mounted centrally of the assembly. The shield consists of a rigid piece of insulating material, such as Bakelite, Micarta, or other suitable material. The enlarged shaft portion 66 rests on the central portion of the shield which is suitably recessed to accommodate it, and bolts 86 and 88 pass through adjacent blocks 36 and the shield 84. When the nuts on the bolts 86, 88, are tightened, an extremely strong and rigid assembly results.

The casting 78 houses a ratchet assembly (Fig. 6) which facilitates sure operation of the switch and imparts a "feel" to the hand of the operator, thereby enabling fast operation of the switch without the necessity of actually observing the position of the handle.

A roller 90 (Figs. 4 and 6) is journaled on the base 10 on the outer side thereof. The roller is engaged by the cam recesses 92 of a pair of ratchet arms 94, 96, carried by the casting 78. The arms 94, 96, are pivotally mounted in oppositely disposed, side-by-side relation and are of such length that the ends opposite the mounting ends engage washers 98, 100, carried by the mounting pins 102, 104. Coil springs 106, 108, are disposed in suitable recesses in the casting 78 and bear on the ratchet arms such that the latter are urged downwardly into contact with the roller 90. The arms are prevented from dropping out of the housing when the handle structure is removed from the base 10 by the washers 98 and 100. The casting 78 is fastened to the shaft 64 by means of a set-screw inserted through the tapped hole 110.

The cams 60 and 62 are provided with depressions 112, 114, etc., which are adapted to receive the rollers 58 in various positions of the handle 80. As will be understood from Figs. 2 and 5, the contact arms 46 are held in open circuit position against the action of the springs

48 when the circular portions of the cams 60, 62, are in engagement with the rollers 58. Swinging of the knob 82, thereby rotating shaft 64, also rotates the cams; and when the rollers 58 enter the depressions or recesses 112, 114, etc., of the cams, the springs 48 urge the arms 46 into circuit closing position thereby bridging the respective pairs of contacts 38 in accordance with the particular arrangement of cam recesses.

At the same time, of course, the ratchet arms 94, 96, travel over the roller 90 which successively engages the recesses 92 and the higher portions of the arms, and thus a feel is transmitted to the operator and, in addition, the handle assembly is retained under pressure of the springs 106, 108, in any selected position of rest. This latter feature is important from the safety standpoint.

Electrical conductors are brought into the switch through the conduit coupling 116 which is preferably disposed at one end of the base 10. The switch may be wired in any number of ways in accordance with the type of motor or other electrical apparatus to be controlled. The particular embodiment illustrated provides for two speeds forward, two speeds reverse and "off." The contours of the cams 60 and 62 may be designed to actuate the contact arms 46 in any desired sequence in accordance with movement of the handle 80, it being understood that coil springs 48 will move the arms 46 to bridge the pairs of contacts 38 whenever the respective rollers 58 engage a recess in cams 60 or 62. It should be noted that the contacts 38 are bridged by bars 50 which are self-leveling and that the arms 46 themselves carry no current.

When the switch is assembled, it is substantially sealed against entry of dirt and moisture, the cover 16 fitting tightly on the flange of base 10 and the shaft 64 being sealed at the bearing 76. Disassembly of the switch for inspection or repair is exceedingly simple. Removal of cap screws 118 permits removal of cover 16. It is then a simple matter to remove the screws 32, whereupon the entire saddle assembly may be removed as a unit along with the side pieces 22, 24, and the handle and ratchet assembly. Ordinarily, no further disassembly will be required, but if it is, the power conductors may be removed from the binding posts by loosening screws 42, and the handle assembly is removable by inserting a screwdriver in recess 110. Removal of screws 26 and 34 and bolts 86 and 88 will complete the disassembly. Reassembly is correspondingly simple.

It will be understood that while we have described the use of castings for the base, cover, saddle, etc., stampings, weldments or other fabricated construction may be used.

It will thus be seen that we have provided a rugged, yet simple, multiple-throw switch which is positive in action and easy to disassemble and reassemble. While we have shown but one of the many forms the invention may assume, it will be understood that, by so doing, we do not intend to limit our invention in any way except as set forth in the appended claims.

We claim:

1. In a switch, a base, a saddle assembly mounted in said base, said saddle assembly comprising a saddle member, a plurality of stationary contacts mounted on said member, a contact arm pivotally mounted on said member, a contact bridging member carried by said arm, means carried by said member for swinging said arm about its pivotal mounting whereby certain of said con-

tacts may be bridged by said bridging member, and removable fastening elements for securing said saddle assembly to said base.

2. In an electrical switch, a saddle member, a pair of stationary contacts mounted on oppositely extending portions of said saddle member, a pair of contact arms pivotally mounted on said saddle member and extending oppositely from the central portion thereof, a bridging member carried by each of said arms in such position that the respective pairs of contacts are bridged in one position of said arms, and means for selectively actuating said arms about their pivots comprising a cam disposed in engagement with both of said arms.

3. In an electrical switch, a pair of oppositely extending pivotally mounted contact arms, a single cam for selectively swinging said arms between "off" and "on" positions, a lobe on said cam adapted to selectively engage said arms to move either or both to "off" position, depressions in said cam adapted to selectively engage the respective arms to move one or the other to "on" position, said depressions being disposed on said cam such that less than 90° of movement of said cam will actuate one or the other of said arms.

4. In an electrical switch, a pair of oppositely disposed swinging contact arms, a handle for selectively swinging said contact arms between "on" and "off" positions, a pair of detent members disposed in operative relationship with said handle for yieldably retaining said handle in an "off" position and a plurality of "on" positions, and means associated with said members and handle for causing one of said members to exert pressure on said handle when the latter is in an "on" position and both of said members to exert pressure on said handle when the latter is in "off" position.

5. The combination set forth in claim 1 wherein a ratchet mechanism is operatively associated with said handle and said mechanism is also carried by said saddle member.

6. In a switch, a base, a saddle assembly mounted in said base, said saddle assembly including a pair of oppositely disposed side pieces, circuit make-and-break elements mounted on said saddle, actuating mechanism for said elements mounted on said side pieces, a cover for said elements and mechanism having edge portions adapted to mate with said base, and side pieces thereby to provide a dirt-proof structure.

7. In a switch, a base, a saddle member mounted in said base, stationary circuit make-and-break elements carried by said saddle, bridging elements carried by said saddle, a pair of side pieces carried by said saddle, a cam shaft carried by said side pieces, cams on said shaft, and means mounted on said saddle and operatively associated with said cams for actuating said bridging elements.

8. The combination set forth in claim 7, wherein said elements are mounted on insulating blocks disposed on said saddle in side-by-side relation, a shield of insulating material mounted vertically between said elements.
